Henry Ford.

El. Davis
ATTORNEY.

UNITED STATES PATENT OFFICE.

HENRY FORD, OF DEARBORN, MICHIGAN.

PUMP.

Application filed June 1, 1926. Serial No. 112,762.

The object of my invention is to provide improvements in pumps of simple, durable and inexpensive construction.

A further object of my invention is to provide a pump adapted to create a partial vacuum and which eliminates valves having moving parts or moving parts for the operation of the valves in so far as is possible.

A further object of my invention is to provide a pump adapted to create a partial vacuum and which is especially adapted to be used in connection with an internal combustion engine and to be operated by one of the shafts thereof.

Still a further object of my invention is to provide a vacuum creating pump designed to be moved in one direction by a cam and to be moved in the opposite direction by a spring so that the moving parts may be as simple as possible and as effective.

With these and other objects in view, my invention consists in the arrangement, construction, and combination of the various parts of my improved pump as described in the specification, claimed in the claims, and illustrated in the accompanying drawings, in which:

Figure (1), shows a vertical, central, sectional, longitudinal view through my improved pump, some of the parts associated therewith being shown in dotted lines.

Figure (2), shows a vertical, transverse, sectional view, taken on the line 2—2, of Figure (1).

Figure (3), shows a vertical, transverse, sectional view, taken on the line 3—3, of Figure (1).

Figure (4), shows an end view of the pump, the cam mechanism for operating same being in the foreground.

Figures (5), (6), (7), and (8), are diagrammatic views illustrating respectively the position of the pump during the intake stroke, the intake proper, the compression stroke, and the exhaust.

Referring to the accompanying drawings, I have illustrated portions of an internal combustion engine such, for instance, as a crankcase thereof, by the reference numeral (10), the crankcase being provided with bosses (11) designed to receive tappets (12), which are actuated by cams on a cam-shaft (13). The parts just described are of ordinary construction in connection with

internal combustion engines and especially those of the automotive type.

The housing (10) is provided with an opening (14) designed to have the flanges (15) of the pump housing (16) bolted or otherwise secured thereto for the purpose of making a liquid tight joint between the housing (16) and the housing (10) and for forming the support for my improved pump. A substantially cylindrical member (17) is rigidly secured within the housing (16) in any suitable manner but in the form of device here shown this is accomplished by swaging in the outer edges of the housing (16) as at (18) around a contracted portion of the member (17) whereby a rigid and liquid tight connection is formed. This cylindrical member (17) is provided adjacent to its outer end with a threaded opening (19), which terminates in a passageway (20) which extends axially through the member (17) from the opening (19) to a position at about the center of the member (17). At the inner end of the passageway (20) a transverse passageway (21) is formed in the member (17), whereby the opening (19) and the passageways (20) and (21) may together form a continuous passageway from the exterior of the pump to a position at about the center thereof. These passageways and the opening I shall hereinafter generally refer to as an intake port.

At the opposite end of the member (17) is an axial passageway (22), which extends from the inner end of the member (17) along its axis to a position adjacent to but spaced from the inner end of the passageway (20). The outer end of the passageway (22) is connected by transverse passageways (23) with the exterior of the member (17).

A cup-shaped member (24) is mounted on the member (17) for reciprocation with its open end disposed adjacent to the outer end of the member (17). This cup-shaped member (24) I shall hereafter call the piston of my improved pump. It is provided adjacent to the inner end thereof with an annular flange (25), which is designed to form a shoulder against which a coil spring (26) may bear. The housing (16) adjacent to the piston (24) is of substantially greater diameter than said piston, whereby this coil spring (26) may be housed between the housing (16) and the piston (24), and thereby by the tendency of the spring (26) to expand

will tend to force the piston (24) off from the member (17) or inwardly. An offset or shoulder (27) adjacent to the outer end of the member (17) forms a stop for the outer 5 end of this spring to enable it to accomplish its function.

A plurality of outlet ports (29) are formed in vertical alignment at intervals in the piston (24), and at a position aligned substantially with the passageway (23) in the member (17) when the piston is in its outer position, as illustrated in Figure (1) and Figure (8). The interior of the piston (24) may be formed with an annular groove (30) 10 adjacent to these outlet ports (29) to aid in the discharge of the compressed air from my improved pump. A plurality of compression retaining expansion rings (31) may be disposed in appropriate grooves in the member (17) for the purpose of rendering my improved pump more efficient should it be desired. In the form of device here illustrated I have shown one of these rings (31) 15 adjacent to the outer end of the piston (24) and one adjacent to the inner or closed end thereof.

The camshaft (13) is provided with a cam (32), which is designed to bear against the closed end of the piston (24) for the purpose 20 of actuating the piston in one direction, that is outwardly.

In the practical operation of my improved vacuum creating pump, it will be understood 25 that this pump is especially designed to be used in connection with the fuel supply system of an internal combustion engine of the type wherein a partial vacuum is used to draw the fuel from a fuel supply tank to a second tank which furnishes a reservoir from 30 which the fuel may feed by gravity to the carburetor of the engine. This pump is designed to furnish the necessary partial vacuum and is connected into the fuel supply system at the place where a vacuum is necessary by any suitable fitting which may be 35 connected with the threaded opening (19). When the engine is operating of course, the camshaft (13) will rotate, thereby rotating the cam (32). Movement of the cam (32) 40 to the position shown in Figure (1) and Figure (8) will move the piston (24) to its outer position against the pressure of the spring (26) and further rotation of the shaft (13) will move the cam (32) out of the path of 45 the piston (24) so that the spring (26) will force the piston inwardly. As soon as the piston (24) has moved a distance equal to the width of the passageway (23) the exhaust ports will be closed by the movement 50 of the piston and a partial vacuum will be created in the space between the inner end of the member (17) and the closed end of the piston (24), as may be seen by referring 55 to Figure (5) adjacent to the reference numeral (33). As the piston (24) continues 60

its outward movement to the full amount, this vacuum creating chamber (33) will expand until the piston reaches the position illustrated in Figure (6). At this point, 70 ends of an elongated annular groove (34) in the inner wall of the piston (24) will come opposite respectively to the ends of the passageway (21) and the passageway (23), whereby the partial vacuum in the space (33) will tend to draw in air from the inlet port to the space (33) as indicated by the arrows in Figure (6).

As the cam (32) continues its rotation, due to the actuation of the shaft (13), the space (33) becomes smaller as the cam during the second half of its revolution tends to press the piston (24) outwardly. As soon as the piston (24) travels a distance equal to the width of the passageway (23), communication between the chamber (33) and the inlet port is closed and any air in the chamber (33) becomes compressed by the movement of the piston (24), this compression increasing as the chamber (33) diminishes, until the piston reaches substantially 80 the position shown in Figure (8), at which time this chamber (33) has practically no dimensions, as the closed end of the piston (24) comes almost into contact with the end of the member (17). Just prior to the time that the piston (24) reaches this position, however, the exhaust ports (29) and the piston (24) come opposite the passageway (23), thereby permitting the air from the chamber (33), which is under compression, to escape down the passageway (22) and out through the passageway (23) and exhaust ports (29). Further rotation of the cam 90 merely causes a cycle of the events just described to be repeated, whereby the parts connected with the inlet opening (19) will be effected by a substantially constant partial vacuum.

Many advantages arise from the use of my improved vacuum creating pump in that the ordinary construction of an internal combustion engine need be altered only in two ways to have this pump; namely, by providing the mounting opening (14) in the crankcase and by adding an additional cam (32) on the cam shaft (13). The mounting of the pump is readily accomplished by merely removing or replacing the bolts or screws holding the flange (15) to the crankcase. The piston itself is actuated in one direction by the cam and in the other direction by the spring, so that complicated or expensive moving parts are largely eliminated and wear is largely compensated for automatically. No additional moving parts for the valves or the valve actuations are required, so that the device is extremely simple and not at all likely to become clogged with dirt or the like. If the device should 110 become clogged, the moving parts, namely, 115

the piston (24) and spring (26) may be readily removed to accomplish the necessary cleaning, and the various passages are all in such shape that they may be readily cleaned. 5 It should also be noted that the partial vacuum created by this pump will remain substantially constant relative to the engine speed, so that the fuel supply will be governed by the engine speed rather than by 10 the partial vacuum created by the intake of the engine itself.

Some changes may be made in the arrangement and construction of the various parts of my improved device without departing 15 from the spirit of my invention, and it is my intention to cover by the following claims such changes as may be reasonably included within the scope thereof.

I claim as my invention.

20 1. In a pump for creating a partial vacuum, a member having an inlet port therein and a passageway therethrough adjacent to the end thereof opposite the inlet port, a cup shaped piston member mounted 25 on the first described member, said piston member having exhaust ports therein and a recess designed to permit communication between the inlet port and the passageway in the first described member when the piston is 30 in one of its positions, and means for reciprocating said piston.

2. In a pump for creating a partial vacuum, a member having an inlet port therein and a passageway therethrough adjacent to the end thereof opposite the inlet port, a cup shaped piston member mounted 35 on the first described member, said piston member having exhaust ports therein and a recess designed to permit communication between the inlet port and the passageway in the first described member when the piston is 40 in one of its positions, a cam device adapted to move said piston in one direction, and

resilient means for urging said piston in the opposite direction.

3. In a partial vacuum creating device adapted to be associated with an internal combustion engine having a crankcase and a camshaft, a cam formed on said camshaft, a pump housing mounted on said crankcase housing, a substantially cylindrical member fixed in said housing, a cup shaped piston member mounted on said cylindrical member for reciprocation, said piston being adapted to be moved in one direction by the said cam, a spring mounted within said housing and adapted to move said piston in the opposite direction, and means for operatively connecting said cylindrical member and piston, including passageways formed within said piston and cylindrical member whereby reciprocation of the piston will create a partial vacuum.

4. In a pump a substantially cup shaped housing member, a substantially cylindrical member fixed within said housing member, said cylindrical member having a plurality of passageways therethrough, designed to form an intake port and a second passageway, a cup shaped piston mounted for 70 reciprocation on said cylindrical member, said cup shaped piston having an exhaust port therein and a recess designed in one position of the piston to permit communication between the inlet port and passageway in the cylindrical member, a spring mounted between the piston and the housing, designed to yieldingly urge the piston in one direction of its movement, and means for positively urging the piston in the opposite direction 80 of its movement.

Signed at Dearborn, in the county of Wayne, State of Michigan, this 25th day of May, 1926.

HENRY FORD.
